UNITED STATES PATENT OFFICE.

JAMES E. BURDEN, OF WORCESTER, MASSACHUSETTS.

CENTERING DEVICE.

Application filed November 27, 1920. Serial No. 426,868.

To all whom it may concern:

Be it known that I, JAMES E. BURDEN, a citizen of the United States, residing at the city of Worcester, in the county of Worcester and State of Massachusetts, have invented new and useful Improvements in Centering Devices, of which the following is a specification.

This invention relates to improvements in 10 geometrical instruments and more particularly to center finding devices.

One of the objects of my invention is to provide a simple, inexpensive and highly efficient device in the nature of a simplified 15 tool that can be carried about in a person's vest pocket so as to be ready for instant service whenever required.

Another object of my invention is to provide a simple center finder constructed of 20 very few parts that enables the center of round stock to be very readily and easily obtained without measurement.

With the above and other objects in view 25 my invention consists in the arrangement, combination, and details of construction disclosed in the drawings and specification and then more particularly pointed out in the appended claim.

In the drawings wherein similar reference 30 characters designate similar parts indicated in the respective views,

Figure 1 is a top plan view of my invention,

Figure 2 is an edge elevation thereof,

Figure 3 is a bottom plan view of my invention,

Figure 4 shows the stock adapted to be centered by means of my invention,

Figure 5 is a cross section through my 40 invention,

Figure 6 shows the manner in which the round stock can be centered,

Figure 7 shows my instrument applied to round stock,

Figure 8 shows another detail in the application of my instrument to round stock, and,

Figures 9 and 10 show top and bottom plan views respectively of my invention 50 showing stock applied properly.

Referring to the drawings which are merely illustrative of my invention A designates a sheet metal frame in the shape of a half circle and an equilateral quadrilateral cut diagonally and a longitudinal sheet metal strip B is secured to said frame at

its central median line. My invention thus consists of two simple parts.

The frame A has a pair of oppositely inclined sides 1 and 2 which converge to 60 a point at the lower end thereof, while the upper ends form an arcuate portion 3 which integrally connects these two oppositely inclined sides 1 and 2 as shown clearly in the figures. The longitudinal strip B has a 65 beveled edge 9 secured flush with the terminal edge of the side 2 of the frame A being secured at this point by a rivet 8 or in any other desirable manner by means of which it may be secured to the frame A by the 70 flush connection. 10 designates the point of the strip 11 where it coincides with the point of the triangle of the device. The strip B is secured at its opposite end by a rivet 5 that enters the frame A so that its 75 outer arcuate edge 6 will be flush with the arcuate portion 3. While thus positioned the edge 11 of this strip will bisect the triangle of the same and particularly pass 80 through the center of the instrument so that the edges 11^b and 12 of this triangle will be equally distant from the edge 11 of the strip B.

C designates the instep represented by the thickness of the main frame A. Any round 85 object or polygonal object is adapted to be introduced into the instep C, Fig. 5, so as to rest upon the strip B and so as to rest also at the opposite edges and at two points or two edges against the inclined edges 11^b 90 and 12 of the triangular portion of the frame. Take the round object 12^a as an example; after it is positioned so as to lie upon the strip B and made to contact the edges 11^b and 12 as aforesaid it will be 95 found that the edge 11 of the strip b will pass through the center of this round object so that the mechanic by means of a prick punch or scribe may draw a line by scratching or otherwise on the round object by 100 guiding the scribe or punch against the edge 11 of the strip B; then by turning the object around another line will be similarly scratched while the object still engages the strip 11 and contacts at two points against the inclined edges 11^b and 12, this line being 105 designated as at 14. These lines or any other lines converge as at 19 and intersect at the center of the object as at 16. By means of the punch the mechanic can then 110 form a niche in the center of the object in a well known manner.

2

It will thus be seen that I have provided a simple and handy centering device that will instantly without measurement locate the center of any round object or regular 5 polygonal object,—a device which is complete in itself and not an adjunct to another part and will operate efficiently and accurately so as to be fool proof. Numerous modifications may be employed, without de- 10 parting in principle from the details of construction herein disclosed.

What I desire to claim by Letters Patent is:

15 A centering device of the character de- scribed including two parts, one part comprising a sheet metal frame designed in the shape of a half of an equilateral quadri- lateral cut diagonally and a half circle re- spectively, the other part comprising an

elongated metal strip longitudinally ar- 20 ranged with respect to the first mentioned part and being provided with a bevelled edge at one end which is secured flush with the terminal edge of one side of the frame with the point of the bevelled edge termi- 25 nating with the point of the apex of the half quadri-lateral portion, the opposite end of the strip having an arcuate shaped edge and being secured to the half circle portion so that the longest side edge of the strip 30 divides the first mentioned part into equal parts.

In witness whereof he has hereunto set his hand this tenth day of January, 1920.

JAMES E. BURDEN.

Attested:

WILLIAM E. BAFF,
W.M. A. BLANCHARD.
